PACKAGING TRAY FOR A LOBSTER

Allan Ray Clouston, 6845 Monkland Ave.,
Montreal 28, Quebec, Canada

Filed Jan. 20, 1970, Ser. No. 21,010

Term of patent 14 years

Int. Cl. D9—04

U.S. Cl. D9—222

FIG. 1

FIG. 2

FIG. 3

FIG. 4

FIG. 1 is a side elevation of a packaging tray for a lobster showing my new design;

FIG. 2 is a plan view thereof;

FIG. 3 is a end view thereof; and

FIG. 4 is a bottom view thereof.

I claim:

The ornamental design for a packaging tray for a lobster, substantially as shown.
